UNITED STATES PATENT OFFICE.

CARLETON W. NASON, OF MONTCLAIR, NEW JERSEY, AND GEORGE E. KNOWLES, OF BROOKLYN, NEW YORK.

DESIGN FOR A BASE OF PUMPING-ENGINES.

SPECIFICATION forming part of Design No. 12,406, dated August 9, 1881.

Application filed July 7, 1881. Term of patent 14 years.

To all whom it may concern:

Be it known that we, CARLETON W. NASON, of Montclair, Essex county, New Jersey, and GEORGE E. KNOWLES, of the city of Brooklyn, 5 Kings county, and State of New York, have invented a new and Improved Design for Bases of Pumping-Engines, of which the following is a specification.

In the drawings, Figure 1 is a plan view, 10 Fig. 2 is a side view, and Fig. 3 is an end view, of our newly-designed base.

The base is composed of the main portion A, which is hollow, and the bed-plate B. The box A is of rectangular form in its general outline. One end is recessed in the form of a segment of a globe or formed with curved brackets a a, and the plate B is formed with a semi-circular recess, b, to correspond. The brackets a are thus an elongation of the sides of the 20 base. At the same time the base, when viewed from the side or top, has a light and graceful

appearance. The plate B is also provided with a circular opening, c, formed with a flange. The edges of the plate B are preferably formed with a downwardly-extending flange, e, of bevelled form. 25

Having thus described our invention, we claim as new and desire to secure by Letters Patent—

1. The design for bases of pumping-engines 30 shown and described, consisting of box A, having brackets or prolongations a at one end, and a top plate, B, shaped to correspond.

2. The design for bases of pumping-engines 35 shown and described, which consists in the recessed end of the body A and bed-plate B.

CARLETON W. NASON.
